(74) Attorney, Agent, or Firm — Banner & Witcoff, Ltd.

(57) **CLAIM**

The ornamental design for a display screen with graphical user interface, as shown and described.

DESCRIPTION

The FIGURE is a front view of a display screen with graphical user interface showing my new design.

The broken line shown in the Figure illustrates the display screen and forms no part of the claimed design.

1 Claim, 1 Drawing Sheet(56)
